UNITED STATES PATENT OFFICE.

HENRY JOSEPH, OF MILWAUKEE, WISCONSIN, ASSIGNOR, BY MESNE ASSIGNMENTS,
TO ROSA JOSEPH, OF MILWAUKEE, WISCONSIN.

WASHING MACHINE.

Application filed September 7, 1923. Serial No. 661,503.

The invention is primarily devised as a means for lubricating the vertical spindle of a rotary washing machine, and is embodied in a construction which permits the 5 lubricant to be applied at the lower end of the spindle and automatically fed upwardly thereof so as to lubricate the said spindle throughout its entire area of contact with the fixed tubular post in which it is mounted 10 to rotate.

The invention also embraces the loose arrangement of a sleeve upon the said fixed post, to permit rotation of the latter when engaged by the fabrics being washed and 15 prevent destruction of such fabrics under strains imposed by the dolly.

These and other details of construction will be hereinafter described, and the novelty of the invention will be pointed out in 20 the appended claim.

In the drawing:

Figure 1 is a vertical sectional view through the central part of a rotary washing machine of a type now well-known, the 25 spindle and some of its attached parts being shown in full.

Fig. 2 is a transverse sectional view on the line 2—2, Figure 1.

Referring to the drawing, the numeral 10 30 indicates the bottom of the tub of a portable washing machine. The said bottom is bored centrally for the reception of the vertical spindle 11 carrying the agitating dolly, not shown, at its upper end. The spindle 11 35 is guided and supported for rotation in an elongated tubular post 12, which latter by means of clamping nuts 13 and 14 is securely positioned in the central bore of the bottom 10 of the tub. Gaskets or washers 15 and 40 15' through which the said post is passed are applied at the opposite sides of the bottom 10, and when the nuts 13 and 14 are screwed in position, a leak-proof connection is made. At the same time the tubular post 45 12 is rigidly secured in operative position.

A cap nut 16 is threaded upon the upper 50 end of the post 12, a disc 17 fixed upon the upper end of the spindle 12 resting upon the said cap nut, and supporting the spindle in vertical position. The disc 17 is provided upon its upper face with an eccentrically arranged pin 18 which latter is designed to receive thereon the usual agitating dolly, and to impart movement thereto in the rotation

of the spindle. A fly wheel 19 is mounted 55 on the lower end of the spindle 11 at a point immediately below the bottom 10 of the tub. The extreme lower end of the said spindle is connected by reducing gears to the shaft of an electric motor, which may be conveniently mounted upon the frame of the washing machine, and arranged so as to give movements of continuous rotation to the spindle 11.

Near its opposite ends the spindle 11 is 60 provided with circumferential grooves 20 and 20' for the reception of packing rings 21, inter-positioned between the opposite ends of the tubular post 12 and the clearance at the base of the threaded portions of the 65 nuts 16 and 14. An elongated groove 22 extending circumferentially of the spindle 11, connects the annular grooves 20 and 20', such elongated groove being designed to effect 70 vertical movement of lubricant applied to the spindle 11 at the lower end of the groove 22, so as to efficiently lubricate the surface of the said spindle at the points of its contact with the tubular post 12. The packing rings 21, before referred to limit the movement of the lubricant to the area desired. 75

One side of the nut 14 at the under side of the bottom 10 of the tub is bored for the reception of an oil cap or grease cup 23, containing any suitable lubricant. The lower 80 end of the post 12 is provided with an opening in alignment with the oil cap or grease cup so that the lubricant may flow from the latter into contact with the surface of the rotating spindle exposed thereto. The best 85 results are secured by forcing the feed of the lubricant, and it will be apparent that thorough lubrication of the spindle is secured. The assembly of the parts is such that the water in the tub, although it may 90 rise to the cap 16, cannot reach the interior of the tubular post 12, the packing ring 21 at the upper end of the spindle serving the double purpose of retaining the oil and excluding the water. 95

The under side of the cap nut 16 and the upper side of the nut 13 are provided with concentric seats 24 and 25 for the reception of a tubular sleeve 26 adapted to have free 100 rotation about the fixed post 12. The purpose of this construction is to prevent strain upon the fabrics being washed, due to the pull thereon by the agitating dolly. In the 105

absence of such a freely rotating sleeve, the fabrics would cling to the fixed post and be torn in the movements of the dolly.

Modification in the arrangement of the parts may be made without departing from the spirit of my invention.

Having thus described my invention, what I claim and desire to secure by Letters Patent of the United States, is:

10 In a washing machine, a tubular post fixed in the bottom of the tub thereof, a spindle mounted for rotation in the said post, a re-

cessed nut upon the post bearing against the bottom of the tub, a recessed cap nut threaded upon the upper end of the post, and a 15 freely rotating sleeve surrounding the said post and confined between and seated in the recesses in the said nuts, such sleeve being rotatable by the pull of the fabrics thereon during the operation of washing.

In testimony whereof, I have signed my name at Milwaukee, this 31st day of August, 1923.

HENRY JOSEPH.
